UNITED STATES PATENT OFFICE

THOMAS E. MURRAY, OF NEW YORK, N. Y.

ELECTRIC CUT-OUT.

No. 913,755.

Specification of Letters Patent.

Patented March 2, 1909.

Application filed September 2, 1908. Serial No. 451,440.

To all whom it may concern:

Be it known that I, THOMAS E. MURRAY, a citizen of the United States, residing at New York, in the county of New York and State of New York, have invented a certain new and useful Improvement in Electric Cut-Outs, of which the following is a specification.

The invention is a cut-out embodying a base block and suitable removable fuse-plugs. The construction is such that circuit may be broken in either the positive or negative conductor of a three wire system; or in both, by simply reversing the position of the proper fuse-plug, or in the latter case, the positions of both fuse-plugs. The fuse-plug or fuse-plugs, whether in position to open or to close circuit, remain in the base block and are locked therein. The condition of the circuit, whether open or closed, is visually indicated by suitable marks, and the indication follows necessarily upon the placing of the fuse-plugs in one position or the other. The sockets and receptacles into which the fuse plugs enter, and the connections therein, are completely guarded by the plugs themselves whether the plugs be placed in one position or the other. The plugs in either position prevent removal of the cover, and in either position, they are locked in place. The connections of the conducting wires are completely guarded by shields which are also locked in place. A single device locks in place the plugs, the cover and all the shields, so that it is impossible to tamper with the electrical connections without removing said device and necessarily making an exposure of that fact, through the breakage of a seal.

The invention consists in the construction more particularly pointed out in the claims.

In the accompanying drawings—Figure 1 is a plan view of the device, showing the removable fuse-plugs in position to close circuit in the positive and negative conductors. Fig. 2 is a cross section on the line x, x , of Fig. 1. Fig. 3 is a plan view, showing the circuit connections in the base block, the fuse-plugs and cover being removed. Fig. 4 is a partial plan view, showing the removable fuse-plugs in the position they occupy when circuit is broken in the positive and negative conductors. Fig. 5 is a cross section on the line y, y , of Fig. 4. Fig. 6 is a top perspective view of one of the fuse-plugs taken from above; and Fig. 7 is a similar

view of one of the fuse-plugs taken from below. Fig. 8 shows the locking rod and seal.

Similar numbers and letters of reference indicate like parts.

1 is a base block preferably of porcelain having, in its under side, recesses for the reception of the metal strips 2, 3, 4. In the upper side of the base block are formed two pairs of rectangular sockets 5, 6 and 7, 8, in each of which sockets is a metal clip 9 having upwardly projecting arms or sides. To the clip in socket 6 is secured by a screw, one end of the plus conductor 11 of a three wire system. To the clip in socket 5, is secured by a screw, one end of the metal strip 2. To the clip in socket 8, is secured by a screw, one end of the minus conductor 13. To the clip in socket 7 is secured by a screw, one end of the metal strip 4.

Between the pairs of sockets 5, 6 and 7, 8, is a receptacle 10 into which enters the end of the neutral conductor 12, which is secured in place and electrically connected to one end of strip 3 by screw 14. Also in the upper side of the base block are three transverse recesses 17, formed by walls 21, which walls do not extend to the level of the upper surface of the base block. Entering said base block and extending through said recesses are the three house wires 18, 19, 20, received between pairs of metal plates 22. Said plates are secured in place and are respectively connected by screws to the strips 2, 3, 4. A removable flat covering plate 23 rests upon the recess walls 21, so that one edge of said plate completes one bounding wall of the sockets 5 and 7, and receptacle 10, the upper surface of said plate coming flush with the upper surface of the base block. Also in the upper side of the base block is a recess 23^x and a receptacle 24 in which are openings 25 for the reception of the screws or bolts by which the device is secured to a wall of a building or any other suitable support.

The two fuse-plugs A, B, Figs. 6 and 7, are alike in construction. The case of each has an arched upper portion 26, on one side of which is a flange 27. The bottom on its under side is flat and there are two projections 28, 29 thereon, each provided with a metal envelop 30. In each plug is a transverse opening 31. The projections 28, 29 are of such dimensions and so placed as to enter the sockets 5, 6 or 7, 8, and establish electrical contact with the clips 9 therein. The receptacles 10 and 24 are so placed and

of such dimensions as that when the plugs are reversed, as hereinafter described, to break circuit, said receptacles will receive the projections 28 and 29. Within each 5 plug case is disposed an arched fuse 32, of any suitable construction, having its terminals connected to the metal envelope 30 on projections 28, 29.

Referring now to Figs. 1 and 2, the fuse-plugs A, B, are here shown with their projections 28, 29 inserted in the sockets 5, 6 and 7, 8, thus establishing circuit from the main conductors 11, 13, through the strips 2, 4, to the house wires. The flange 27 of plug 10 A then extends over receptacle 10 and the flange 27 of plug B over receptacle 24, thus 15 completely closing said receptacles.

In Figs. 4 and 5, each fuse-plug is reversed in position, the projections 28 and 29 of plug 20 A entering receptacle 10, and the projections 28 and 29 of plug B entering receptacle 24. The flange 27 of plug A then extends over sockets 5, 6 and the flange 28 of plug B over sockets 7, 8, thus completely closing said 25 recesses. In this position of the plugs A, B, circuit is broken between the conductors 11, 13 and the strips 2, 3.

In order to indicate visually whether circuits are closed or broken, I may mark on the 30 cover 23, in any suitable way, the word "On" opposite the sockets 5, 6 and 7, 8, and the word "Off" opposite the receptacles 10 and 24: and also mark or form in relief on the upper curved surfaces of the fuse plugs, double pointed arrows 33. When the fuse plugs are in the position to close circuit, as shown in Fig. 1, the arrows 33 point to the word "On", and when in position to open circuit, as in Fig. 4, the arrows point to the word 40 "Off".

The cover 23 is put in place before the fuse-plugs, so that said plugs over-lap a portion of said cover, as shown in Fig. 1, and so prevent the removal of said cover from the 45 base block.

The fuse plugs A, B, and cover 23 are locked in place by the following means. On the base block 1 are upwardly projecting lugs 34, 35, having openings. Through said 50 openings and also through the openings 31 in the fuse-plugs A, B, is passed a locking rod 36 having a head 37 at one end, and an opening at the other end, which opening receives the shackle of any suitable seal 38, after the rod 55 has been inserted, so that it is impossible to remove or alter the position of either plug, or to remove the cover 23 without first breaking the seal and taking out the rod.

In order to prevent access to the connections at the several junctions of the main and house conductors, I form, around the openings through which said conductors pass in the several walls of the base, a countersink or recess. Into these recesses fit the 65 enlarged ends of tubular metal shields 39, 40,

41. The shield 39 incloses the main conductors 11, 12, 13, and the shields 40, 41, the house wires. These three shields are all locked in place by the single locking rod already described. The shield 39 has an arm 70 42, which extends over the base block and between the fuse-plugs A, B, and is provided with an opening near its end for the reception of said rod. The shields 40, 41 each have an arm 43 projecting from one side, 75 which arms are also provided with openings and are suitably placed outside the lugs 34, 35, to receive said rod.

I claim:

1. In an electric cut-out, a base having 80 two sockets and circuit terminals therein, a removable fuse-plug having its ends constructed to fit in said sockets, a receptacle in said base for said plug ends when said plug is removed from said sockets, and means on 85 said plug for closing said sockets when said plug is disposed in said receptacle, and for closing said receptacle when said plug is disposed in said sockets.

2. In an electric cut-out, a base having 90 two sockets and circuit terminals therein, a removable fuse-plug having its ends constructed to fit in said sockets, a receptacle in said base constructed to receive both of said ends when said plug is removed from said 95 sockets, and a flange on said plug: the said parts being constructed so that when said plug ends are respectively seated in said sockets, said flange shall close said receptacle, and when said ends are seated in said receptacle, said flange shall close said sockets.

3. In an electric cut-out, a base having two sockets and circuit terminals therein, a removable fuse-plug having a substantially 100 semicircular case, a horizontal flange on one side of said case, projections on said case constructed to fit in said sockets, and a receptacle in said base for said projections when said plug is removed from said sockets: the said flange being of width sufficient to cover said 110 receptacle when said projections are in said sockets and to cover said sockets when said projections are in said receptacle.

4. In an electric cut-out, a base having two sockets and circuit terminals therein, a removable fuse-plug having its ends constructed to fit in said sockets, a receptacle in said base for said plug ends when said plug is removed from said sockets, and means constructed and operating to lock said plug in 115 either position.

5. In an electric cut-out, a base having two sockets and circuit terminals therein, a removable fuse-plug having its ends constructed to fit in said sockets, a receptacle in 125 said base for said plug ends when said plug is removed from said sockets, means on said plug for closing said sockets when said plug is disposed in said receptacle and for closing said receptacle when said plug is disposed in 130

said sockets, and means constructed and operating to lock said plug in either position.

6. In an electric cut-out, a base having two sockets and circuit terminals therein, a removable fuse plug having its ends constructed to fit in said sockets, a receptacle in said base for said plug ends when said plug is removed from said sockets, means on said plug for closing said sockets when said plug is disposed in said receptacle and for closing said receptacle when said plug is disposed in said sockets, and means on said plug and said base for visually indicating the make or break in circuit in accordance with the location of said plug in said sockets or in said receptacle.

7. In an electric cut-out, a base having two sockets and circuit terminals therein, circuit connections disposed in said base, a removable cover for closing the portion of said base containing said circuit connections, a removable fuse-plug having its ends constructed to fit in said sockets and shouldered to overlap said cover, and means for locking said fuse plug in said base.

8. In an electric cut-out, a base having two sockets and circuit terminals therein, circuit connections disposed in said base, a removable cover closing the portion of said base containing said circuit terminals, a removable fuse-plug having its ends constructed to fit in said sockets, a receptacle

in said base for said plug ends when said plug is removed from said sockets, means on said plug for closing said sockets when 35 said plug is disposed in said receptacle, and for closing said receptacle when said plug is disposed in said sockets, the said plug being shouldered to overlap said cover when in either position, and means for locking said 40 fuse-plug when in either position to said base.

9. A base block, two groups of circuit conductors entering openings in adjacent walls of said block, a detachable tubular shield enclosing each group of conductors and surrounding said openings and in contact with said block, and a device for locking said shields to said block.

10. In an electric cut-out, a base block, a removable fuse-plug therein, circuit conductors, removable shields for protecting said conductors at their entrances into said base block, circuit connections in said block for said conductors, a removable cover for closing the portion of said base block containing said circuit connections, and a single device for locking said cover, fuse-plug and shields in place on said base block.

In testimony whereof I have affixed my signature in presence of two witnesses.

THOMAS E. MURRAY.
